221,036
TONGUE SCRAPER

N. Dasan Potti, 94 Debra, Buffalo, N.Y. 14207

Filed Dec. 23, 1969, Ser. No. 20,621

Term of patent 14 years

Int. Cl. D24—99

U.S. Cl. D83—12

FIG. 2.

FIG. 4.

FIG. 3.

FIG. 5.

FIG. 1 is a top plan view of a tongue scraper, showing my new design;

FIG. 2 is a side elevational view thereof;

FIG. 3 is an end elevational view thereof;

FIG. 4 is a fragmentary cross-sectional view taken on the line IV—IV of FIG. 1; and

FIG. 5 is a cross-sectional view taken on the line V—V of FIG. 1.

I claim:

The ornamental design for a tongue scraper, substantially as shown.
